PULL HANDLE FOR DOORS, DRAWERS, AND THE LIKE

David F. James, Redondo Beach, Calif., assignor to Hyer
Hardware Mfg. Co., Anaheim, Calif.

Filed Sept. 10, 1971, Ser. No. 179,606

Term of patent 14 years

Int. Cl. D8—06

U.S. Cl. D8—166

FIG. 1.

FIG. 2.

FIG. 3.

FIG. 1 is a front elevational view of a pull handle for doors, drawers, and the like, showing my new design;

FIG. 2 is an elevational view of one of the similar sides thereof; and

FIG. 3 is an elevational view of one of the similar ends thereof.

I claim:

The ornamental design for a pull handle for doors, drawers, and the like, as shown and described.
